SWELL LOUVER ACTION FOR ORGANS

Henry Willis and Aubrey Thompson-Allen,
London, EnglandApplication February 2, 1934, Serial No. 709,527
In Great Britain September 8, 1933

17 Claims. (Cl. 84—347)

This invention relates to improvements in actions for effecting or controlling the movements of swell louvers in organs.

The object of this invention is to move the swell louvers or shades of organs by electrical connections between the organ and a detached console so as to obtain a perfect crescendo and diminuendo over any desired period of time without steps, stations or jerks in the opening or closing of the louvers such as occur when all the louvers of a swell box are moved step by step, or when the louvers are moved in succession singly or in groups. This invention provides means whereby the organist may change the positions 15 of the louvers by an uninterrupted gradual progressive movement of the same away from the closed towards the open position, or vice versa, by operating a pedal or like member. The movement of the louvers may, at will, be made as 20 quickly or as slowly as is desired. The louvers may be checked in their movement at any point, so that the positions in which the louvers can be brought to rest is not limited to a given number of predetermined points. The louvers when 25 checked at the desired point remain locked or stationary until again put in motion by an appropriate movement of the controlling device.

Heretofore the louvers of swell boxes have been moved or adjusted by mechanical connections to 30 vary the volume of the sound from time to time or progressively for a time variable at will, to obtain a crescendo or diminuendo of the volume of the sound from the organ pipes in the swell box. In small organs where the console is placed 35 close to the organ, a mechanical transmission of motion from the swell pedal to the louvers may be practicable. However, in a large organ, where there is a large and heavy set of louvers to be moved, a mechanical transmission is impracticable, partly owing to the inertia which has to 40 be overcome in order to move the louvers and the difficulty of checking by an opposing force the momentum of the louvers when they have been set in motion, so that complete control over such momentum cannot be conveniently attained by the force which can be applied by the 45 foot of the organist acting on a pedal, and therefore the control which can be exerted on the nature of the performance of a crescendo for diminuendo passage is limited.

Again, when dealing with an organ with a detached console, (such as a church organ having the console placed on the opposite side of the chancel or in some other place remote from where 50 the swell box is placed) it is rarely possible to

obtain a satisfactory mechanical connection between the console and the swell box, apart from the fact that if this is possible there is still some inconvenience in the case of a large swell box arising from inertia and momentum, as above 5 mentioned.

In the accompanying drawings:

Figure 1 is a longitudinal sectional view of a chamber enclosing a motor for actuating the swell louvers of an organ in accordance with this 10 invention.

Figure 2 shows a transverse section of the same.

Figure 3 is a detail view of a controlling or swell pedal arranged to close electrical contacts 15 effecting the setting of valves selectively admitting air to the said motor, and

Figure 4 is an end view of the blades serving as the electrical contacts.

As shown in Figures 1 and 2, 10 is a wind motor comprising a movable board 11 enclosed in a chamber 12, the interior space within the motor 10 being in open communication through an aperture 13 with another chamber 14. The movable board 11 has a rod 15 secured thereto and 20 guided at one end in a packed guide 16 provided on a wall of the chamber 12. This rod 15, which passes across and extends out from the chamber 14 through an aperture 17 sealed by a flexible diaphragm 18, is connected to one end of a 30 lever 19 pivotally mounted on a bearing 20 carried by a frame 14a secured to a suitable part of a wall of the chamber 14, the lever 19 at its opposite end being connected to a rod 19a which extends to the louvers (not shown) so that movement of the board 11 effects a corresponding movement of the louvers. 35

Wind is admitted to the chambers 12 and 14 through a series of valve-controlled ducts opening into the chamber 12 through orifices 21, and into the chamber 14 through orifices 22. Each group of orifices 21, 22 comprises orifices of different cross-sectional area. A suitable arrangement of valve 23 for controlling the passage of wind from a wind chest 24 through a duct 25 to a corresponding orifice 21, or 22, is shown in Figure 2, and all the ducts of the orifices 21, 22 may be provided with similarly arranged valves. The valve 23 is supported by a flexible diaphragm 26 attached at its edges to a bridge 27, and a spring 28 urges the valve to its closed position. A rod 29 attached to the valve extends through a hole in the wall of the duct 25 and carries a washer or disc 30 adjustable on the rod to limit the opening movement of the valve. Pressure in 50 55

the wind chest 24 acts also on the inner side of the diaphragm 26, through a port 31 in a box 33 open at its ends to the wind chest 24, and through a duct 32 which can be put in communication 5 with the port through a valve 34. When the valve 34 is moved to its closed position a valve 35 carried on the same rod opens to put the duct 32 in communication with the atmosphere and the pressure in the chest 24 acting on the diaphragm 26 then opens the valve 23 against the spring 28. The valve 34 is closed by the operation of an electromagnetic device hereinafter described acting in any convenient manner to effect movement of the rod carrying the valves 10 34, 35. When the valve 35 is closed and the valve 34 opened, wind pressure on both sides of the diaphragm 26 is balanced and the valve 23 is held closed by the spring 28.

The electrical circuits for individually controlling the several valves 23 comprise contacts in the form of spring blades, each contact being appropriated to a corresponding valve, and these contacts are arranged in two groups, Figures 3 and 4, a spring contact 36 is provided for each valve in a duct 25 opening through an orifice 21 into the chamber 12 and a spring contact 37 is provided for each valve opening through an orifice 22 into the chamber 14. One set of contacts 36 are mounted on one side of a bar 38 20 while the other set of contacts 37 are mounted on the other side of this bar. There is thus provided between the two sets of contacts, a space in which a conductor bar 39 can be moved. This conductor bar is carried on a slide bar 40 attached to a swell pedal 41 pivotally mounted on a pin 42 and movable by the foot of the organist between the extreme positions indicated in broken lines. A link 43 attached to the pedal 41 at one end is supported at its other end between springs 44, 45 which urge the pedal to a central or neutral position and thus move the bar 39 to a position between and out of contact with all the contacts 36, 37 which are arranged at different distances from the bar 39 when the latter is in 30 its central or neutral position so that the circuits through the contacts of the group 36 or the group 37 are closed in succession and cumulatively as the bar is moved in either one or the other direction. The position of each contact may 40 be adjusted by means of a corresponding screw 46 so as to vary, as may be required, the distance through which the bar 39, after contacting with one blade, must be moved before it makes contact with the next in order. When the pedal is 50 pressed by the toe of the organist the bar 39 closes the circuit or circuits through one or more of the contacts 36 according to the distance through which the pedal is moved and similarly when pressed by the heel of the organist, one or more of the circuits through the contacts 37 60 is closed. When pressure is not being exerted by either the heel or toe of the organist, the springs 44, 45 as the case may be, return the pedal to a neutral position and the bar 39 is carried away from the contacts 36, 37 so that all the circuits through these contacts are open and at such times the valves 34, 35 fall by gravity to positions (Figure 2) such that the pressure on each diaphragm 26 is balanced and the valves 23 are 70 closed by the springs 28.

The valves 34, 35 can be raised, by energizing an electromagnetic device 35a, so that the valve 34 closes the port 31. The duct 32 is thus opened to the atmosphere by the opening of the valve 35, and 75 wind in the chest 24 acting on the diaphragm 26

then opens the valve 23 to admit wind to the duct 25.

The electric leads connecting the contacts 36, 37 to the electromagnets for moving the rods carrying the valves 34, 35, the electromagnets themselves and a source supplying electric energy to the circuits can be arranged in any suitable manner and comprise parts of any suitable construction, the wiring of these parts not presenting any difficulty and not requiring any precautions not usually taken in electrical installations of a simple and common character so that detailed illustration of the same is unnecessary.

Each chamber 12, 14 is provided with an exhaust valve 47 carried on a diaphragm 48 and is urged to its closed position by a spring 49. A duct 50 leads from a chamber 51 in which the spring is arranged and a valve (not shown) is provided in the said duct. When, by movement of the bar 39, the valve controlling any orifice 21 20 is opened by the electromagnetic device to admit wind to the chamber 12, the valve in the corresponding duct 50 is set by an electrically operated device, for example, in the same circuit to admit wind to its chamber 51 and the valve 47 25 is held firmly on its seat by the pressure acting on the diaphragm 48, assisting the spring 49, thus preventing escape of air past this valve. At this time all the orifices 22 opening into the chamber 14 are closed and the valve of the corresponding 30 duct 50 is set to put its spring chamber 51 in communication with the atmosphere so that air pressure in the said chamber is reduced and allows the valve 47 to be opened by the wind in the chamber 14 overcoming the spring 49. Thus the board 35 40 41 can be moved by wind entering the chamber 12, as the chamber 14 is emptied. Similarly when any orifice 22 is opened the corresponding exhaust valve 47 is held closed and the exhaust from the chamber 12 can open.

When the chambers 12, 14 are not receiving air through any of the orifices 21, 22 the exhaust valves 47 are held against their seats by the springs 49. On the return of the bar 39 to its central position after any of the orifices 21, 22 45 have been opened by contact of this bar with any of the contacts 36, 37 all the orifices 21, 22 are closed and the exhaust valves 47 are held closed by their springs, and if at this time the louvers are in motion the momentum of the moving parts 50 is checked by the attenuation of the air in one of the chambers 12, 14. The movement is thus arrested without shock by the air cushion, and the louvers will remain in the position in which they are brought to rest until one or another of the 55 orifices 21, 22 is opened again to move the board 11.

When it is desired that the louvers shall be entirely closed, in order to ensure that the felt faces thereof shall be under compression and not 60 merely resting in contact with their seatings, an orifice 54 is provided to admit wind to the chamber 14 under the control of a valve opened by the closing of an electrical circuit including a contact 55 carried on the lever 19 and a stationary 65 contact 56. Simultaneously with the opening of the orifice 54, wind may be admitted to the corresponding duct 50 to ensure the closure of the corresponding exhaust valve, whilst the valve of the duct 50 corresponding to the chamber 70 12 is open to the atmosphere so that the exhaust valve of the chamber 12 can open against the thrust of the spring 49. The wind admitted to the chamber 14 thus keeps the louvers firmly shut. So long as the circuit through the contacts 55, 75

56 is closed, opening of the louvers is impeded by the air entering the chamber 14 through the orifice 54. In order to break the circuit through the contacts 55, 56 as soon as one of the orifices 21 is opened, wind is simultaneously admitted to the chamber 51 through the duct 50, and a small motor 57 is moved by wind admitted through the duct 58 to effect the opening of a switch in the same circuit as the contacts 55, 56 with the result that the orifice 54 closes and remains closed so long as any of the orifices admitting wind to the chamber 12 remains open.

The rod 19a moved by the plate 11 affords a means for moving the louvers positively in both directions. The provision of a number of separate orifices allows the speed of movement of the plate 11 to be varied as required, the control being further assisted by providing orifices of progressively increasing cross-sectional area in the order in which the orifices are opened by closing the bar 39 successively on the spring contacts 36, 37. When only one orifice 21, 22 is open, the chamber supplied with wind through this orifice is filled slowly with a consequent slow movement of the plate 11. By opening more than one orifice at a time the rate of admission of air is increased and the plate 11 is moved more quickly.

If the pedal 41 is moved in one or the other direction from its central or neutral position so as to cause the bar 39 to make contact with only one of the spring contacts 36, 37, whilst the organ is being played, the louvers will move slowly and a slow crescendo or diminuendo effect will be obtained. If the pedal is at any time allowed to return to its central position the louvers will remain in the positions they have reached at the moment the pedal is thus moved. By moving the pedal so as to close all the contacts 36, or 37, quickly or simultaneously, the louvers will be moved quickly so that a forte or piano volume of sound issues from the swell box.

By reason of the movements of the louvers being controlled by electro-pneumatic action there is no tendency of the operative parts to bind or stick as may happen when the pedal acts on the louvers through a mechanical connection, and the louvers are opened or closed in an uninterrupted or regular progressive movement which is arrested without shock by reason of the cushioning effect of the air in the chambers 12, 14.

We claim:

1. An action for effecting movement of swell louvers in organs, comprising a wind chest, a wind motor, a series of ducts admitting wind from the wind chest to the wind motor, valves respectively controlling the passage of wind through each duct, and individually controlled means for opening and closing the said valves in a successive order.

2. An action for effecting movement of swell louvers in organs, comprising a wind chest, a wind motor including a movable board, a series of ducts admitting wind from the wind chest to move the said board in one direction, a series of ducts admitting wind from the wind chest to move the said board in the opposite direction, valves respectively controlling the passage of wind through each duct, and means for opening in succession the valves corresponding to one series of ducts while the valves corresponding to the other series of ducts are held closed.

3. An action for effecting movement of swell louvers in organs, comprising a wind chest, a wind motor, a valve opened by wind from the wind

chest for admitting wind to the motor, a spring for closing the valve, and means for reducing the air pressure acting on the same side of the valve as the said spring in order to allow the valve to open.

4. An action for effecting movement of swell louvers in organs, comprising a wind chest, a wind motor, a valve opened by wind from the wind chest for admitting wind to the motor, a spring for closing the valve, and an electrically controlled valve for reducing the air pressure acting on the same side of the first mentioned valve as the said spring to permit opening of this valve.

5. An action for effecting movement of swell louvers in organs, comprising a wind chest, a wind motor, ducts admitting wind from the wind chest to the motor, groups of valves respectively controlling the passage of wind through each duct, one group of valves operating to effect movement of the motor in one direction and another group operating to effect movement in the opposite direction, and electrically operated means for effecting the opening of the valves of one group while the valves of the other group remain closed.

6. An action for effecting movement of swell louvers in organs, comprising a wind chest, a wind motor, ducts admitting wind from the said wind chest to the motor, groups of valves respectively controlling the passage of wind through each duct, one group of valves operating to effect movement of the motor in one direction and another group operating to effect movement in the opposite direction, and electrically operated means for opening the valves of either group while those of the other group remain closed, including circuit closing contacts for effecting the opening of the valves, the said contacts being arranged in groups corresponding to the groups of valves.

7. An action for effecting movement of swell louvers in organs, comprising a wind chest, a wind motor, ducts admitting wind from the said wind chest to the motor, valves respectively controlling the passage of wind through each duct, electrically operated means including circuit closing contacts for effecting movement of the valves, a contact bar having the said contacts arranged in groups on opposite sides thereof, and means urging the said bar to a position between these groups out of contact with all the said circuit closing contacts.

8. An action for effecting movement of swell louvers in organs, comprising a wind chest, a wind motor, ducts admitting wind from the said wind chest to the motor, valves respectively controlling the passage of wind through each duct, electrically operated means including circuit closing contacts for effecting movement of the valves and an oscillatory contact bar having the said contacts arranged in groups on opposite sides thereof, the individual contacts of each group being variously spaced from the bar when the latter is in a position between these groups out of contact with all the said circuit closing contacts.

9. An action for effecting movement of swell louvers, in organs, comprising a wind chest, a wind motor, ducts admitting wind from the said wind chest to the motor, valves respectively controlling the passage of wind through each duct, electrically operated means including circuit closing contacts for effecting movement of the valves, an oscillatory contact bar having the said contacts arranged in groups on opposite sides thereof, and means for adjusting individual contacts to

- different positions away from the bar when the latter is in a central position.
10. An action for effecting movement of swell louvers in organs comprising a reciprocating member operative to control the admission of wind to a wind motor, means including an electric circuit and circuit closing contacts for effecting movement of the said member, an oscillatory contact bar having the said contacts arranged in groups on opposite sides thereof, the individual contacts of each group being variously spaced from the bar when the latter is in a central position out of contact with all the said circuit closing contacts, and means for moving the bar away from its central position to make contact successively with the circuit closing contacts on the side towards which it is thus moved.
11. An action for effecting movement of swell louvers in organs, comprising a wind chest, a wind motor, including a movable board, a series of ducts of different cross-sectional areas for admitting wind from the wind chest to the wind motor, and means for admitting wind through a series of the ducts opened in succession at will, to control the speed of movement of the said movable board.
12. An action for effecting movement of swell louvers in organs, comprising a wind chest, a wind motor including a movable board, a series of ducts for admitting wind from the wind chest to the wind motor, means for admitting wind through a series of ducts, and means for opening the said ducts for the passage of wind in a predetermined order.
13. An action for effecting movement of swell louvers in organs, comprising a wind chest, a wind motor including two chambers and a movable board, a series of ducts forming separate communications between the wind chest and each of the said chambers and a separate exhaust valve for each chamber urged towards its seat by a spring.
14. An action for effecting movement of swell

louvers in organs, comprising a wind chest, a wind motor including two chambers, a series of ducts forming separate communications between the wind chest and the said chambers, an exhaust valve for each chamber urged towards its seat by a spring and means for supplementing the spring by wind supplied from the wind chest.

15. An action for effecting movement of swell louvers in organs comprising a wind chest, a wind motor including a movable board, separate series of ducts admitting wind to the motor to move the said board in opposite directions respectively, valves respectively controlling the passage of wind through the said ducts, means for opening the said valves in order to effect movement of the board in either direction and means operated on the arrival of the board in one extreme position to maintain the board in this position.

16. An action for effecting movement of swell louvers in organs, comprising a wind chest, a wind motor including a movable board, separate series of ducts admitting wind to the motor to move the said board in opposite directions respectively, valves respectively controlling the passage of wind through the said ducts, means for opening the said valves in order to effect movement of the board in either direction and a supplementary duct and valve operated on the arrival of the board in one extreme position to maintain the board in this position.

17. An action for effecting movement of swell louvers in organs, comprising a wind chest, a wind motor including a movable board, valved ducts for admitting wind to the motor to move the said board in opposite directions respectively, a supplementary valved duct opened by the arrival of the board in one extreme position to maintain the board in this position and means for closing the said supplementary duct in order to release the said board.

HENRY WILLIS.
AUBREY THOMPSON-ALLEN.
